UNITED STATES PATENT OFFICE.

GEORGE H. BROWN, OF WARWICK, RHODE ISLAND.

GRIPPER.

1,334,015.

Specification of Letters Patent. Patented Mar. 16, 1920.

Application filed June 19, 1919. Serial No. 305,307.

To all whom it may concern:

Be it known that I, GEORGE H. BROWN, a citizen of the United States, residing at Warwick, in the county of Kent and State of Rhode Island, have invented certain new and useful Improvements in Grippers, of which the following is a specification.

My invention relates to grippers for printing presses, and has for its essential objects 10 the inclusion in a gripper of means for not only holding the paper in its place on the platen but also means for contemporaneously performing auxiliary operations upon the paper being printed, such as cutting, 15 punching, perforating, embossing and creasing. Further objects are compactness, inexpensiveness, strength, and facility of manipulation.

To the above ends essentially my invention 20 consists in such parts and in such combinations of parts as fall within the scope of the appended claims.

In the accompanying drawings which 25 form a part of this specification,

Figure 1 is an elevation of my gripper mounted on the gripper rocking bar, a portion of the latter being broken away,

Fig. 2, a side elevation of the same, showing the rocking bar in section,

Fig. 3, a section on line 3—3 of Fig. 1,

Fig. 4, a front elevation of the gripper engaged with a creasing member,

Fig. 5, a section of the same on line 5—5 of Fig. 4.

Figs. 6 and 7, side elevations of portions of a creasing and perforating blade respectively.

Fig. 8, an elevation of the gripper in which is mounted a punch.

Figs. 9 and 10, a side elevation and a central vertical section respectively of a punch.

Fig. 11, a plan of an embossing die,

Fig. 12, a section on line 12—12 of Fig. 11,

Figs. 13 and 14, a plan and a transverse section respectively of a type holder and contents,

Fig. 15, a perspective view tab cutter, and

Fig. 16, a front elevation of a modified form of my invention.

Like reference characters indicate like parts throughout the views.

In the drawings 17 is the usual rocking bar of a printing press of the usual construction provided with a longitudinal slot 55 18 through which passes the bolt 19. The bolt also traverses a hole 20 in the base or

enlarged end 21 of the gripper. By means of a nut 22 in conjunction with the head 23 of the bolt the parts are adjustably clamped at any position longitudinally of the rocking 60 bar. This attaching means is not exclusive.

The gripper proper comprises integral with its enlarged attaching portion 21 a bar or rod 25 of preferably rectangular cross section provided with threaded openings 26, in this instance four in number, disposed at equal intervals throughout the rod. In these openings are screws 28 slideable through openings 29 similarly disposed in a clamping bar or rod 30. The heads 31 70 of the screws engage the bar 30.

In the form of gripper member shown in Fig. 4 is included, clamped between the rods 25 and 30, a creasing member or plate 33 provided at intervals with holes 34 to admit 75 the screw 28 therethrough. The blade 33 has an operating portion 36 which projects laterally beyond the plane of the rods 25 and 30.

When perforating of the paper is to be 80 performed there is embodied in the gripper, in place of the blade 33, a like blade 38 provided with openings 39 for screws and having a series of cutting edges 41.

In Fig. 8 the gripper is provided with a 85 device for cutting circular holes in the paper being printed. This device is a die comprising a rectangular body 43 provided with an annular cutting edge or elevation 44, extending from which through the body is an 90 opening 45 to admit passage of the disks cut from the paper. The block is preferably frictionally clamped between the rods 25 and 30 with the operating portion projecting laterally beyond the plane of the 95 rods 25 and 30.

In like manner may be mounted in the gripper an embossing die comprising a rectangular body 46 provided in its upper or operating face 47 with a figured depression 100 48. This member is also clamped in such a manner that the operating portion 47 projects laterally beyond the rods 25 and 30.

In like manner may be mounted in the gripper an oblong rectangular holder 50 105 carrying type 52 whose operating portions laterally project.

When it is desired to cut portions of the paper being printed, as for instance, to form tabs thereon, a plate 54 is provided having a 110 lateral arm 55 with an upturned lip 56 upon its extremity. On the face of the plate is

an arcuate blade 57 with a sharp cutting edge or operating face 58. The blade is fast in posts 59 on the face of the plate. The lip 56 may be clamped between the rods 25 and 30 of the gripper and the operating portion 58 projects beyond the plane of the gripper rods.

The gripper may comprise, as shown in Fig. 16, more than one clamping rod, as 62, 10 in all respects like rod 30, except that if preferred it may be shorter. Thus several operations may be performed at once. The illustration shows a perforating blade 38 and a punching die 43.

15 It will be understood that a series of grippers may be attached to a single rocking bar 17.

It is apparent that the gripper may support in an analogous manner not only a 20 type holder but electrotypes printing through an ink ribbon and such other devices as may be used for effecting paper visible or mechanically. Such action is better performed if the devices employed are 25 free from contact with the ink rollers of the press.

The gripper operates in the usual manner. That is to say, it is located between the bed

of the printing press and the platen, and as the latter advances to the bed the die or 30 other implement mounted in the gripper is forced against the paper or other material being printed. A showing of the bed and platen is herein omitted, because the construction and operation of these parts are 35 known to all versed in the art.

I claim:

1. In a printing press, the combination of a rocking bar, a gripper rod mounted on the bar laterally thereof provided with spaced 40 threaded openings, a clamping rod provided with spaced openings, and clamping screws disposed parallel with the rocking bar extending through the openings in both rods.

45 2. In a printing press, the combination of a rocking bar, a gripper rod mounted on the bar, a clamping rod, clamping screws connecting the rods, and members embraced by the rods provided with operating portions 50 projecting laterally beyond the faces of the rods.

In testimony whereof I have affixed my signature,

GEORGE H. BROWN.
